(57) **CLAIM**

The ornamental design for an integrated tabbed note and clip kit, as shown and described.

DESCRIPTION

FIG. 1 shows a perspective view of a first embodiment of a design for an integrated tabbed note and clip kit.

FIG. 2 shows a top view of the first embodiment.

FIG. 3 shows a front view of the first embodiment.

FIG. 4 shows a right-side view of the first embodiment. A left-side view of this embodiment is a mirror image of this figure.

FIG. 5 shows a back view of the first embodiment.

FIG. 6 shows a bottom view of the first embodiment.

FIG. 7 shows a perspective view of a second embodiment of a design for an integrated tabbed note and clip kit.

FIG. 8 shows a top view of the second embodiment.

FIG. 9 shows a front view of the second embodiment.

FIG. 10 shows a right-side view of the second embodiment. A left-side view of this embodiment is a mirror image of this figure.

FIG. 11 shows a back view of the second embodiment.

FIG. 12 shows a bottom view of the second embodiment.

FIG. 13 shows a perspective view of a third embodiment of a design for an integrated tabbed note and clip kit.

FIG. 14 shows a top view of the third embodiment.

FIG. 15 shows a front view of the third embodiment.

FIG. 16 shows a right-side view of the third embodiment. A left-side view of this embodiment is a mirror image of this figure.

FIG. 17 shows a back view of the third embodiment.

FIG. 18 shows a bottom view of the third embodiment.

FIG. 19 shows a perspective view of a fourth embodiment of a design for an integrated tabbed note and clip kit.

FIG. 20 shows a top view of the fourth embodiment.

FIG. 21 shows a front view of the fourth embodiment.

FIG. 22 shows a right-side view of the fourth embodiment. A left-side view of this embodiment is a mirror image of this figure.

FIG. 23 shows a back view of the fourth embodiment; and,

FIG. 24 shows a bottom view of the fourth embodiment.
